HANDLE CONSTRUCTION FOR BOXES AND CARTONS

James V. Mitchell, Chicago, Ill., assignor to Packaging Corporation of America, Chicago, Ill., a corporation of Illinois

Application October 31, 1952, Serial No. 317,920

4 Claims. (Cl. 229—52)

This invention relates to certain new and useful improvements in a handle construction for boxes and cartons which are especially designed for use for transporting garments and other articles.

A principal object of the invention is to provide a handle structure for such a box in which the handle element may be quickly and easily attached to the box by an unskilled person without the exercise of any undue labor or time.

As boxes of the type herein referred to are not sold to the customer but are given without charge for the convenience of the customer in transporting a garment or other article it will be appreciated that it is most desirable that the handle structure be simple in construction to afford economical manufacture thereof. It is, therefore, a further object of this invention to accomplish such an object.

It is a further object of this invention that the handle structure be of such character as to permit its incorporation in boxes and cartons of various constructions and designs.

It is also an object of the invention to provide a handle structure which may not only be quickly and easily affixed or attached to the box but also one which will be of sufficient strength for the purposes for which it is intended.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a conventional garment box, having incorporated therein my improved handle structure;

Fig. 2 is a fragmentary top plan view of the same with the handle removed and with a portion of the outer flap likewise removed;

Fig. 3 is a fragmentary perspective view of the box illustrated in Fig. 1 showing the first step in applying the handle element to the box;

Fig. 4 is a perspective view similar to Fig. 3 showing the succeeding step in applying the handle element to the box; and

Fig. 5 is a fragmentary perspective view similar to Figs. 3 and 4 but showing the handle element in applied position with respect to the box.

In accomplishing the several objects of my invention, it is to be understood that the handle structure may be incorporated in boxes of various designs and construction. I therefore do not want to be limited to the precise construction of the box illustrated in the drawings of this application. Such box has been illustrated for explanatory purposes and is of a conventional construction which includes a cover section 10 and a bottom section 11 arranged in telescopic relation with respect to each other.

The box is, as shown, of the collapsible type with the side walls 12 attached to the top wall 13 by means of a slot and tab construction 14. The top wall 13 of the cover section 10 is likewise connected by means of a tab and slot construction 15 to the wall 16 of the bottom section 11.

2

My improved handle construction comprises a pair of spaced apart elongated slots 16' formed in alignment with respect to each other in the top wall 13 of the bottom section 11.

Such structure further includes normally closed slits 18 formed in spaced relation and in alignment with respect to each other in the top wall 13 and in substantial registration with the slots 16'. In stating that the slits 18 are normally closed, I mean by such a statement that the adjacent portions of the wall 13 defining such slits are in substantial contacting relation with respect to each other and are capable of being forced apart to permit the passage therethrough of portions of a handle element to be presently referred to.

Corresponding end portions 19 of the slits 18 terminate into transversely extending normally closed slits 20. Such a construction gives the necessary flexibility to the portion of the wall 13 surrounding the slits 18 when the portions of the handle element are manually forced through the slits 18.

The opposite corresponding end portions 21 of the slits 18 terminate into apertures 22 and 23. These apertures, as hereinafter pointed out, will guide the insertable portions of the handle element into and through the slits.

The aperture 23 is located in alignment and in spaced relation with respect to a keeper aperture 24 formed in the wall 13. The aperture 24 is located in registration with an aperture 24' formed in the top wall 17 of the bottom section 16.

The handle element 25 is preferably formed from a length of wire bent to provide an intermediate portion 26 which is normally grasped by the hand. Extending substantially at right angles to this intermediate portion 26 are leg portions 27. The end portions of the wire length are bent substantially at right angles with respect to the leg portions 27 and in parallel relation to the intermediate portion 26 to provide carriage arms 28 and 28' which are substantially in alignment with respect to each other. The carriage arm 28' is provided with an upturned latching finger 29 adapted to cooperate with the keeper apertures 24 and 24' in the manner presently described.

A handle element constructed substantially as above described is applied to the box in the following manner:

The operator grasps the handle element in the manner shown in Fig. 3 and locates the corner 30 thereof upon the adjacent opening 22. A downward and inclined pressure is now exerted on the handle element to force the carriage arms through the adjacent slit 18 to the position shown in dotted lines Fig. 3. After this has been accomplished the operator then tilts the handle element downwardly with respect to the horizontal so as to locate the arm 28' over the adjacent slit 18. When this has been done the operator continues the tilting movement of the handle element until the arm 28' has passed through the adjacent slit 18. The handle element is then moved downwardly to pass the latching arms 28 and 28' through the slots 16.

From this position the handle element is then shifted in a parallel direction with respect to the wall 13 to locate the latch finger 29 in registration with the keeper apertures 24 and 24' so that when the handle element is moved to the position shown in Fig. 5, the finger 29 will be located in the openings 24 and 24'. In this position of the finger 29 the handle element is prevented from shifting during the carrying of the box or carton.

The web portion 31 of the cover 13 will prevent the handle element from passing entirely through the slits 18 into the interior of the box.

From the foregoing description it will be apparent that I have provided a handle structure capable of accomplishing all of the objects hereinbefore stated.

While I have shown and described the employment of the latch finger 25 and its cooperating openings 24 and 24' and while I deem it advantageous to employ such latching finger and such openings, it is to be understood that, if desired, this latch finger and its cooperating openings may be omitted without departing from the spirit of the invention.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A handle structure comprising a cover and bottom section telescopically related to each other, the top wall of the cover section having a pair of aligned and spaced apart normally closed elongated slits formed therein with corresponding ends of the slits terminating into normally closed slits formed in the top wall and extending transversely of said first slits and said first slits terminating at corresponding end portions into apertures each of a diameter greater than the width of said elongated slits, the top wall of the bottom section having a pair of spaced apart aligned slots formed therein in substantial registration with said slits, and a handle element having an intermediate portion provided with depending legs, said legs terminating in substantially horizontally aligned arms in spaced parallel relation to said intermediate portion and substantially at right angles to said legs, said handle at the point of connection between said legs and said arms insertable in the ends of said first slits and adapted for longitudinal movement therethrough in the direction of said arms, said arms when said handle has been inserted in said slits and moved longitudinally therethrough engageable with said top wall of said bottom section, latch means carried by one of said arms and cooperating with an aperture formed in said cover and bottom sections for latching said handle in operative position when said handle is moved in an opposite longitudinal direction through said first slits.

2. A handle structure comprising a cover and bottom section telescopically related to each other, the top wall of the cover section having a pair of aligned and spaced apart normally closed elongated slits formed therein with corresponding ends of the slits terminating into normally closed slits formed in the top wall and extending transversely of said first slits and said first slit terminating at corresponding end portions into apertures each of a diameter greater than the width of said elongated slits, the top wall of the bottom section having a pair of spaced apart aligned slots formed therein in substantial registration with said slits, the top wall of the cover section and the top wall of said bottom section each having an opening formed therein in spaced relation with respect to the said slits and slots respectively, with the opening of the top wall of the cover section in registration with the opening in the top wall of the bottom section, and a handle element having an intermediate portion provided with depending legs, said legs terminating in substantially horizontally extending aligned arms in spaced parallel relation to said intermediate portion and substantially at right angles to said legs, said handle at a point of connection between said legs and said arms insertable in said apertures at the ends of said first slits and adapted for longitudinal movement therethrough in the direction of said arms, said arms when said handle has been inserted in said first slit and moved longitudinally thereto engageable with said top wall of said bottom section, latch means carried by one of said arms and cooperating with an aperture formed in said opening for latching said

handle in operative position when said handle is moved in an opposite longitudinal direction through said first slits.

3. A handle structure comprising a cover and bottom section telescopically related to each other, the top wall of the cover section having a pair of aligned and spaced apart normally closed elongated slits formed therein with corresponding ends of the slits terminating into normally closed slits formed in the top wall and extending transversely of said first slits and said first slits terminating at corresponding end portions into apertures each of a diameter greater than the width of said elongated slits, the top wall of the bottom section having a pair of spaced apart aligned slots formed therein in substantial registration with said slits, a handle element having an intermediate portion provided with depending legs, said legs terminating in substantially horizontally aligned arms in spaced parallel relation to said intermediate portion and substantially at right angles to said legs, said handle at the point of connection between said legs and said arms insertable in said apertures at the ends of said first slits and adapted for longitudinal movement therethrough in the direction of said arms, said arms when said handle has been inserted in said slits and moved longitudinally therethrough engageable with said top wall of said bottom section, latch means carried by one of said arms and cooperating with an aperture formed in said cover and bottom sections for latching said handle in operative position when said handle is moved in an opposite longitudinal direction through said first slits, said last-named means including a substantially vertically extending finger carried by one of said arms cooperating with said sections to latch said handle in operative position.

4. A handle structure comprising a cover and bottom section telescopically related to each other, the top wall of the cover section having a pair of aligned and spaced apart normally closed elongated slits formed therein with corresponding ends of the slits terminating into normally closed slits formed in the top wall and extending transversely of said first slits and said first slits terminating at corresponding end portions into apertures each of a diameter greater than the width of said elongated slits, the top wall of the bottom section having a pair of spaced apart aligned slots formed therein in substantial registration with said slits, the top wall of the cover section and the top wall of said bottom section each having an opening formed therein in spaced relation with respect to the said slits and slots respectively, with the opening of the top wall of the cover section in registration with the opening in the top wall of the bottom section, and a handle element having an intermediate portion provided with depending legs, said legs terminating in substantially horizontally extending aligned arms in spaced parallel relation to said intermediate portion and substantially at right angles to said legs, said handle insertable in said apertures at the ends of said first slits and adapted for longitudinal movement therethrough in the direction of said arms, said arms when said handle has been inserted in said first slits and moved longitudinally thereto engageable with said top wall of said bottom section, means carried by one of said arms and cooperating with said openings for latching said handle in operative position when said handle is moved in an opposite longitudinal direction through said first slits, said last-named means including a substantially vertically extending finger carried by one of said arms and adapted to be inserted in said openings when said handle is moved in an opposite longitudinal direction through said first slits.
